CIRCUIT CLOSURE FOR TEXTILE
MACHINES, ETC.

Austin E. Stevens, Fall River, Mass.

Application March 1, 1948, Serial No. 12,408

1 Claim. (Cl. 200—52)

1

My invention relates to stop motion operators, signals and the like and has particular reference to such as are operated upon failure of a work supply to a machine, as for instance, material being fed to a sewing machine. It is to be understood, however, that the device has other applications.

In commercial shops using automatically operable, power driven sewing machines one operator will necessarily have to attend to a battery of machines. Thus, it frequently happens that the material being supplied to one machine will be exhausted before the operator realizes what is happening, or there will be occasions when torn material will reach a machine. Under either of these circumstances the sewing machine will continue to operate unless manually stopped by the operator. It is therefore the primary object of the instant invention to provide a very simple, highly efficient and automatically operable means for stopping a sewing machine when the material supplied thereto runs out or a tear or gap appears in such material.

Additionally, I aim to provide a device for the purpose indicated which can be readily installed in operative position clear of the table or other surface upon which the sewing machine is mounted so as to leave such surface free for use of the operator and also to avoid interference with the passage of the material to be sewed.

Still another object of the invention is to provide a material supply-controlled stop motion operator or the like for sewing machines which incorporates an electrical circuit control switch and wherein the latter and associated working parts are enclosed so as to guard against the emission of sparks which would be likely to ignite lint, etc., which is necessarily present in at least some quantity wherever large scale sewing is being carried on.

Additionally, the invention contemplates a device which may and preferably does embody more than one circuit controlling unit so as to be applicable in instances where separate, laterally spaced lengths of material are being fed to separate needles of a sewing machine. An instance of this would be curtain ruffle production when two ruffles are produced at the same time using adjacent needles of the same sewing machine.

The foregoing and other objects are attained by certain novel features of construction, combination and arrangement of the various parts and modes of operation, all of which will be readily understood and appreciated by those skilled in the art upon reference to the accompanying

2

drawings and descriptive matter disclosing the now preferred example of my inventive concept.

It should be understood, however, that the invention is not limited to the particular expression disclosed herein and that various changes and modifications may be made in the illustrated example without departing from the spirit and scope of the subject matter claimed hereinafter.

In the drawings, wherein the same reference characters have been used to designate the same parts wherever they appear—

Fig. 1 is a perspective view illustrating a portion of a commercial two-needle sewing machine, its supporting table and the disposition of my device in operative relationship to the machine and the two lines of curtain ruffle fabric being supplied thereto;

Fig. 2 is a side elevational view of my novel unit in association with a portion of the fabric guide means and the sewing machine supporting table.

Fig. 3 is a top plan view of the unit detached from the sewing machine-supporting table but showing the mounting bracket which is employed for attachment of the unit;

Fig. 4 is a side elevational view looking into the mechanism compartment of one of the casing sections;

Fig. 5 is a view similar to Fig. 4 but showing the companion casing section and a portion of the supporting bracket;

Fig. 6 is a vertical sectional view taken on the line 6—6 of Fig. 3;

Fig. 7 is a fragmentary side elevational view of the rear or bracket-engaged end of the unit;

Fig. 8 is a sectional detail taken on the line 8—8 of Fig. 7 showing a feeler arm-confining element; and

Fig. 9 is a wiring diagram disclosing the circuits employed.

Referring to the drawings by reference characters and turning first to Fig. 1, numeral 10 indicates the head of a standard type of two-needle commercial sewing machine having the laterally spaced, independently operated needles 11, the threads or ends supplied to the needles being indicated by reference character 12.

In the Fig. 1 illustration the machine is being employed in the production of curtain ruffles and each of the needles 11 is having fed to it a separate length of ruffle material 13.

As shown, the respective lengths of ruffle material 13 are each guided to the related needle 11 by means of spaced, oppositely turned and upwardly inclined book cover-like guide elements 55 each of which comprises the inner and outer por-

tions 15, 16, respectively. Each guide provides a material passage space 14 extending for a substantial distance outwardly from the adjacent hinge portions of the book cover-like guide portions 15, 16. The vertical space between the hinge portions of the pair of ruffle guides 15, 16 is indicated by reference character 17.

The respective guides 15, 16 are supported by a frame which includes the upper horizontal member 18 which is secured at its ends to the inclined upper ends 20 of brackets whose horizontal foot portions 21 are screwed or otherwise secured to the sewing machine table or the like 23 (see 22).

Metal strips 24 will be suitably secured to the frame member 18 and said strips have inturned guide-confining ends 24a adapted to overlie top and bottom surface portions of the outer guide-providing portions 16.

My fabric run out detector unit is generally indicated by numeral 30 in Fig. 1. The means for attaching it to the sewing machine support or table 23 comprises the cleat-like strip of metal 25 which is screwed to the table surface as indicated by 26 in Fig. 2. The elongated arm of an L-bracket 27 has a lineal slot 29 adjacent its outer end which is adapted to receive the lineally spaced machine screws 28 whose shanks take in tapped holes adjacent the outer end of the cleat 25. The upstanding foot 27a detachably carries the casing of my unit 30, as will be presently explained.

The detector unit comprehends a two-part casing, as will be indicated by reference to Fig. 6, and Fig. 5 discloses the casing section 31 as being attached to the foot portion 27a of the bracket 27.

Still referring to Fig. 5, the casing section 31 is seen to be generally of square formation and has the top wall 32, the bottom wall 33, front wall 34, and rear wall 35 which latter is adjacent the foot portion 27a of bracket 27. One side of the section 31 is open while the other is defined by the side wall 36.

The other section of the two-part casing of the unit is indicated by 37 and is shown in Fig. 4. Said casing section 37 has the top wall 38, bottom wall 39, front wall 40, rear wall 41, and side wall 42, which latter forms one outer side of the casing as indicated in Fig. 6.

Fig. 4 indicates that the top wall 38 of the casing section 37 has the heavy fibre shelf-like element 43, which latter, as shown in Fig. 6, overlies and provides a shock-absorbing cover for the top wall 32 of the companion casing section 31. This is important because otherwise a blow on casing 30 from above might result in a short circuit.

The bracket-carried casing section 31 of Fig. 5 is illustrated as having its front wall provided with a nut 44a which is welded to the inner surface of same at a point adjacent the bottom wall 33. This nut is adapted to receive the shank of a clamp screw 44 which, when the casing sections 31, 37 are assembled, as in Fig. 6, is adapted to enter the edge slot 40a in the front wall 40 of the casing section 37 of Fig. 4. The inner surface of the rear wall of the bracket-carried casing section has welded thereto adjacent the top wall 32 a nut 45a which is adapted to receive the shank of the screw 45 which secures casing section 32 to the foot 27a of the bracket 27. As indicated in Fig. 4, the rear wall 41 of casing section 37 has the edge slot 41a to receive the shank of bracket screw 45 when casing sections 31 and 37 are assembled.

Regarding the matter of attachment of bracket foot 27a to casing section 31 (Fig. 5) the bracket foot 27a has a lineal slot 46 extending therethrough for reception of the shank of screw 45.

It will be obvious that the provision of slot 46 in bracket foot 27a enables the unit 30 to be adjusted vertically so that the feeler elements (to be referred to later) of the unit will make proper contact with the fabric 13 which is being fed to the sewing machine needles 11.

A washer 47 is disposed on the shank of the screw 45 and interposed between the head of the same and the proximate face of the bracket foot 27a. This may be a spring washer so as to assure against rocking of the casing 30.

Inasmuch as the feeler arm and switch elements of each of the casing sections 31, 37 are identical, a description of one will suffice for both.

Fig. 6 shows that each casing section 31, 37 has its side wall provided with an outwardly extending bearing 48 carrying a sleeve 49 which projects through said respective walls 36, 42. The sleeves 49 are preferably soldered or otherwise made fast in bearings 48.

Journalled in each of the bearing sleeves 49 is a shaft 50 which is of a length to extend beyond both the inner and outer ends of the related sleeve 49.

The outer end of each of the rock shafts 50 receives the bearing end 51 of a feeler arm 52 which is twisted as at 52a to provide the horizontal outer portion 52b whose terminal is weighted as indicated at 53 by means of solder or the like. A set screw 55 serves to clamp the feeler arm bearings 51 on the outer end of the related shaft 50.

Now as to the feeler arm-controlled switches and having reference to Figs. 4, 5 and 6, it will be noted that the inner end of each shaft 50 has secured thereon a collar 54 which is made fast to the inner end of said shaft 50 by means of a set screw 55.

Secured to each collar 54 is the bight portion of a U-shaped bracket 56 whose outwardly extended arms 56a detachably grip the tubular body of a conventional mercury switch 57.

It should be noted that axial movement of each shaft 50 is prevented by engagement of collar 54 with the inner end of the related sleeve 49 in conjunction with engagement of the arm bearing 51 with the outer end of said sleeve.

Each mercury switch 57 is conventional, as has been indicated, and has projecting through insulation into one end of its tubular body (see Fig. 9) the electrically spaced circuit gap-defining electrodes or terminals 58. These terminals 58 have connection with the respective circuit wires 59 and 60 in the case of the switch of casing section 31 (see Fig. 5) while the corresponding wires of the switch of casing section 37 (see Fig. 4) are indicated at 59a, 60a. In each instance the wires 59, 60 or 59a, 60a lead outwardly through a hole 61 in the side wall 36 (or 42) of the associated casing section 37 (or 31), as indicated in Figs. 4 and 5.

It is deemed desirable, but not absolutely necessary, that a wire-retaining cleat 62 be secured to the inner surface of each outer casing wall (36, 42) as indicated at 63, adjacent the wire outlet hole 61 to prevent the wires 59, 60, etc., from being pulled from the associated mercury tube switch 57. Also, the wire-retaining cleats 62 serve to so position the wires 59, 60 as to offer a

minimum of resistance to rocking of the mercury tube-carrying shafts 50.

Referring to Fig. 3, the wires 59a, 60a leading outwardly from the mercury switch 57 of the casing section 37 are attached to the same terminal pieces 64, 65 which are secured to the free ends of the switch wires 59, 60 which lead from the mercury switch 57 of the companion casing section 31.

The respective terminal pieces 64, 65 are secured on binding posts 64a, 65a. The binding posts 64a, 65a are carried by the insulation material disc 66 which is secured to the side wall 36 of the casing section 31 by means of a screw or the like 67, as best shown in Fig. 2.

So long as the fabric 13 is unbroken and is being supplied to the needles 11, as shown in Fig. 1, the feeler arms 52 will be maintained in the position shown in Figs. 2 and 4. This means that the drop of mercury 57a in each tube will be kept at the lower end thereof remote from the terminals 58 (see Fig. 9). Thus, the circuit to the stop motion release 70 will be open. However, if one of the material strips 13 should run out or if a torn place should pass the feeler arm 52, the latter would drop causing the related mercury switch 57 to move clockwise (Fig. 4) to cause the mercury 57a to close the circuit at the tube-contained contacts 58.

The stop motion release may take the form of a solenoid controlled latch 70 for retaining normally disengaged drive clutch elements in operative engagement, or 70 may be a signal.

The outer wall of each casing section has the cleat 71 above the subjacent feeler arm 52 so as to prevent the feeler arm from being actuated very far from contact with the fabric 13.

Also, the side wall of each casing section 31, 37 has a keeper 72 secured thereto adjacent its rear wall 41 (or 35). This keeper 72 has an upper arm which is adapted to be bent inwardly against the adjacent outer wall of the related casing section when the associated feeler 52 is to be used so as to admit of operation of same. Each keeper 72 also has a lower arm 74 to limit clockwise movement of the adjacent feeler arm when the fabric runs out (see Fig. 2).

When only one piece of fabric 13 is being supplied to the sewing machine 10 then only one of the feeler arms 52 would be used and the other would be raised above the top arm 73 of the keeper 72 and the latter would be bent out at right angles to the adjacent side wall of the casing, as indicated in Figs. 7 and 8.

The wiring diagram, Fig. 9, shows that the circuit to the solenoid latch 70 can be closed through either of the mercury switches 57. Battery 75 has one side grounded as at 77 while its other side is attached to binding post 64 of disc 66. The other binding post 65 of said disc 66 has leading from it the wire 78 which is in circuit with the solenoid latch 70, one side of which latter is grounded as indicated at 79. A simple battery powered circuit has been shown by way of example but other circuits are obviously available.

Having thus described my invention, what I claim is:

- 15 A switch for the circuit of a stop motion device for a moving web of material comprising an adjustably mountable casing, said switch casing consisting of two interfitting half sections, sleeve bushings mounted in and extending outwardly from the side walls of each half section of the casing, rock shafts mounted in said bushings, switches mounted on the inner ends of the rock shafts within the casing, web feeler arms attached to the outer ends of the rock shafts and extending outwardly past the rear face of the switch casing and adapted to extend toward the material, weights on the free ends of the feeler arms tending to move the arms to switch closing position, and an L-shaped bracket having its shorter leg adjustably attached to the rear wall of the switch casing and having its longer leg extending from the rear wall of the casing and adapted to be adjustably mounted whereby the feeler arms can be adjustably positioned with respect to the material being fed.

AUSTIN E. STEVENS.
